BI-STABLE RELAY CIRCUIT

Clifford W. Stidger, San Lorenzo, Calif., assignor to Gerber Products Company, Fremont, Mich., a corporation of Michigan

Application July 30, 1956, Serial No. 600,914

1 Claim. (Cl. 317—151)

This invention relates to a means for establishing a pulse controlled bi-stable relay to alternately shift between one of two stable states.

In the past without using electronic control means to convert a pulse input to operate a two stage counter so that each pulse would cause a shift, it was necessary to employ relays in a relative complex circuit or use specially constructed relays with rotating armatures or special mechanical latch mechanisms and the like.

A principal object of this invention is to provide a single relay of conventional design with a novel resistance capacitance circuit to enable the relay to pickup and remain picked up upon being momentarily energized by a control pulse and then to drop out upon being momentarily energized by a succeeding control pulse.

A feature of this invention is that a conventional high power relatively insensitive relay can be used with the novel circuit so transfer points of the relay can be used to directly control high power equipment without the need of intermediate relays and the like.

By employment of the invention a great economy of components is obtained with a resultant simplicity of structure thereby making maintenance and construction more convenient.

Other objects of the present invention will become apparent upon reading the following specification and referring to the accompanying drawing in which similar characters of reference represent corresponding parts in each of the several views.

In the drawings:

The single figure is a schematic view of the preferred embodiment of the invention.

Referring now to the drawing there is shown a relay A of conventional design having a solenoid 13 which operates two or more sets of spring return transfer points 14. The armature 15 of one set of points 14 is arranged to engage a contact 17 when the solenoid is unenergized and engage a contact 16 when energized. It is common in such relays that the solenoids require current of at least a predetermined value to cause their contacts to transfer to picked up condition, but after transferring current of substantially less value will hold the armature in the picked up condition.

In this invention means are provided to regulate the current values to cause the relay armature to pickup, hold and drop out in response to a pulse input. For convenience the current value necessary to pickup the armature will be hereinafter referred to as pickup current and the current value necessary to hold the armature, but insufficient to pickup the armature, will be referred to as holding current. Current value below holding current is referred to as drop out current.

A source of direct current B of a predetermined voltage is supplied for relay A from a positive terminal 21 and negative terminal 22. The solenoid is connected through a resistor 23 to terminal 21 and through a resistor 24 to terminal 22. The resistance values of resistors 23 and

2

24 and solenoid 13 are selected to provide bias current through the solenoid at the holding value. Resistor 24 is of substantially lower value than resistor 23 and is bypassed by a condenser 25, of relatively high value, in the range of 5 mfd. or better, so the circuit will allow a greater voltage swing when subjected to changing current to assist in bringing current through the solenoid to the pickup value when a momentary pulse of pickup current is applied through solenoid 13. Resistor 23 is sufficiently high so when the potential is first applied, although current through resistor 24 will momentarily be bypassed through condenser 25, the relay armature 15 will not pickup.

The positive side of solenoid 13 is connected through a spring urged open push button circuit breaker 26 to armature 15 and through a high capacity value condenser 27, preferably at least 1 mfd. or higher, although a lesser value could be used, to negative terminal 22. Circuit breaker 26 is the relay control switch and may be manually actuated or remotely controlled by a control relay (not shown).

Contact 17 is connected through a resistance 28 to the positive terminal 21 and contact 16 is connected through a resistance 29 to negative terminal 22. By this arrangement when the relay armature 15 is dropped out condenser 27 is charged through resistance 28. While relay A is in dropped out condition and when switch 26 is closed the condenser 27 then discharges through solenoid 13 to bring the current up to pickup value which causes relay A to pickup. When armature 15 is picked up condenser 27 is discharged or bled off through resistor 29. Resistance 29 is of high enough value so while armature 15 is picked up the voltage drop across resistance 29 is insufficient to bring the current through the solenoid down to drop out value so the relay remains picked up with switch 26 closed. When switch 26 is opened condenser 27 is completely discharged through resistor 29. Then when switch 26 is again closed the condenser momentarily offers low enough impedance to shunt the solenoid and bring the solenoid current down to drop out value.

In operation when the electrical power source B is first connected to terminals 21 and 22 the armature 15 remains in dropped out position because the instantaneous current represented by the voltage supply B across the series network resistor 23 and solenoid 13 remains less than the pickup current.

While armature 15 is in drop out position condenser 27 is charged to power source B potential through resistance 28. When circuit breaker 26 is momentarily closed there is an immediate discharge of condenser 27 to send additional current through circuit breaker 26 to solenoid 13 to complement with the holding or bias current to raise the current through solenoid 13 to the pickup current value. The sudden change of current is also seen by condenser 25 which permits a greater voltage swing to assure a pulse of sufficient current to pickup armature 15.

After armature 15 is moved to the pickup position any charge of condenser 27 will bleed off through resistance 29. Thereafter when the circuit breaker 26 is again momentarily closed there is a voltage drop across solenoid 13 through circuit breaker 26, resistance 29 and condenser 27 which drops the solenoid current down to drop out value. The armature 15 then remains dropped out because the values of resistor 28 and resistor 23 are sufficient to keep the relay current to below pickup value and the condenser 27 at the solenoid potential while circuit breaker 26 is closed. Then when circuit breaker 26 is opened condenser 27 is charged to supply B potential through resistance 28.

It can thus be seen that repetitive opening and closure of circuit breaker 26 will cause armature 15 to oscillate between the pickup and drop out position.

It has been found in one particular relay having 1600 ohms D.C. solenoid resistance 20 ma. pickup current was required and 6 ma. holding current. With this relay, for example, it was found that a power source B of 125 volts, resistors 23, 28 and 29 of 10,000 ohms each, resistor 24 of 2,000 ohms, condenser 27 1 mfd. and condenser 25, 20 mfd. was a satisfactory combination of relative values for the component parts. With this combination of values with switch 26 open there is approximately 10 ma. bias current across solenoid 13. Then when switch 26 is closed while the relay is in dropped out condition there is substantially more than 20 ma. across solenoid 13 from discharge of condenser 27 which causes the relay to pickup. Then after the discharge of condenser 27 the current drops to 15 ma. When switch 26 is then open the current falls to 10 ma. and when again closed there is a momentary shunt across the solenoid 13 through condenser 27 which drops the current below 6 ma. so the relay drops out. Then after the relay drops out the current rises to about 8 or 9 ma. until the switch 27 is again open wherein the current raises to 10 ma.

Many transfer points 14 may be employed in mechanically latched relationship with relay A. Each relay transfer point 14 may be used to directly operate motors, generators, electronic equipment and the like. An example of one application of the invention is in an installation where it is desired to have a push button switch arranged to operate a motor so that when the switch is pushed the motor will start and when pushed again will stop and so on repetitively. Another application where the device is useful is in combination with electronic control devices having a pulse output which can close switch 26 by solenoid control.

While there has been described a preferred embodiment of the invention, it is understood that certain modifications of the invention, it is understood that certain modifications and changes may be practiced as limited only by the scope of the appended claim.

It is claimed:

In combination a relay of the type having transfer points including a solenoid actuated armature alternatively engageable with first and second contact points; said armature

ture spring urged in a first position in contact with the first contact point and movable to a second position in contact with the second contact point when the solenoid of the relay is energized by current above a first value and operable to maintain the second position until the current through the solenoid drops below a second value which is less than the first current value; biasing means to energize said relay with current above said second value and below said first value; said biasing means including a first 5 resistance element serially connected between one input terminal of the solenoid of the relay and a first terminal of a power source for the relay; a second resistance element serially connected to a second terminal of the solenoid of the relay and to a second terminal of the power source for the relay; and relay control means to raise the 10 current through the solenoid of the relay above said first value and to lower the current through the solenoid of the relay below said second value; said relay control means including said transfer points, a condenser, a third resistance means, a fourth resistance means and a circuit breaker; said circuit breaker connecting said condenser serially with the second terminal of the power source and the first terminal of the solenoid of the relay when the 15 circuit breaker is in the closed condition of operation; said third resistance means connected to the first terminal of said power source and the first contact point of said transfer points; said fourth resistance means connected to the second terminal of said power source and the second contact point of said relay transfer point; said armature of said relay transfer points connected to said circuit breaker and said condenser to connect said third resistance means to said condenser when said armature is in the first 20 position of operation to charge said condenser through said third resistance means and to connect said fourth resistance means across said condenser to discharge said condenser when said armature is in the second position of operation;
